SHOE-FINISHING MACHINE

Henry B. Greenough, Beverly, Mass., assignor to
 United Shoe Machinery Corporation, Paterson,
 N. J., a corporation of New Jersey

Application December 22, 1936, Serial No. 117,163

9 Claims. (Cl. 12—1)

This invention relates to finishing machines and is illustrated herein as embodied in a machine adapted for finishing the heels of shoes.

The finishing of shoe heels by the use of the usual type of finishing machine requires an operator to present the work successively to a number of different finishing tools arranged at spaced points along a rotating shaft. The losses of time and energy of the operator occasioned by thus moving the work from place to place are material and are factors which it is an object of the present invention to avoid.

To this end, the presentation of the work to the finishing tools of the illustrated machine is effected at one operating point past which the tools are moved in succession as a result of being mounted, in accordance with an important feature of the invention, on a constantly moving carrier or turret, the spacing of the tools on the turret being determined with reference to the different amounts of time required to carry out the various operations so that there is substantially no lost time between the completion of one operation and the arrival at the operating point of the succeeding finishing tool.

As herein illustrated, the finishing tools have a uniform orbital movement with respect to a tool for applying finishing medium to the work, the applying tool being located conveniently with respect to the operating point of the finishing tools whereby a minimum of movement of the operator is required in presenting work to the finishing tools after the work has received an application of finishing medium.

These and other features of the invention will be apparent from the following description when read in connection with the accompanying drawings and will be pointed out in the claims.

In the drawings,

Fig. 1 is a front elevation of an illustrative machine embodying the invention;

Fig. 2 is a side elevation illustrating the finishing tools and the turret upon which they are mounted as viewed from the left-hand side of the machine shown in Fig. 1; and

Fig. 3 is an elevation as viewed from the right-hand side of the machine shown in Fig. 1.

Although the present invention may have application in a machine adapted for performing any finishing operation on a shoe, it is disclosed herein with reference to the finishing of heels of shoes. In the finishing of a shoe heel by the use of the illustrated machine the heel, which will have been prepared for the finishing operation as by scouring and buffing, will first be presented to

a rotating tool 10 which applies a finishing medium, such as wax with or without ink, to the heel. The tool 10 is of the type disclosed in Letters Patent of the United States No. 616,432, granted December 20, 1898, upon the application of Z. Beaudry, and is fixed on the left-hand end of the shaft 12 (Fig. 1) which is supported adjacent to the tool by an arm 14, the latter being fixed to a bracket 16 which is fastened to the machine column 18. The shaft 12 is also rotatably mounted at its right-hand end in a bearing member 20 fixed to the top of the column 18. The shaft 12 is driven by a belt 22 which runs over a pulley 24 fixed to the shaft 12, the belt being driven from any suitable source of power, 15 as an electric motor 26.

The finishing medium is supplied to the tool 10 by a disk 28 rotatably mounted in a medium holder 30, the construction and mounting of which is the same as that of the machine illustrated in Letters Patent of the United States No. 1,636,333, granted July 19, 1927, upon the application of J. F. Standish. As will be fully understood from the above-mentioned Standish patent, adjustment of the disk 28 transversely of the axis of the tool 10 is effected by turning a crank 32 which operates a slide 34 on which the holder 30 is mounted. The slide 34 is mounted in a dovetail slideway formed in a block 36 which may be clamped to the upper end of the bracket 16 in any desired position of adjustment axially of the shaft 12 by means of bolts 38 which pass through elongated slots 40 in the bracket 16. The disk 28 may be driven from the shaft 12 by any suitable means, such as beveled gear connections, as illustrated in the Standish patent, or by means of a belt 42, as in the present machine, which runs over a pulley 44 fixed to the shaft 12 and a pulley 46 associated with the disk 28.

The shoe heel, having had wax applied thereto by the tool 10, is next moved to an operating point in front of the machine to which finishing tools comprising a padding wheel 48, a rand burnishing and beading wheel 50 and two rotary brushes 52, 54 are brought in succession as a result of their being bodily rotated, as will be described later, in an orbital movement with respect to the tool 10 and shaft 12. Each of the above-mentioned finishing tools is journaled in a head 56 and each head is adjustably fixed in a turret comprising a disk 58 having a tubular hub 60 journaled in the bearing member 20 and adapted to receive the shaft 12. A guard member 62 surrounds the heads 56 and has a series of elongated slots 64 adapted to receive screws 66 threaded into the 55

heads 56. Alined radially with respect to the slots 64 are other slots 68 formed in the disk 58 and adapted to receive clamp bolts 70 for securing the heads 56 to the disk 58. The disk 58 is rotated at a relatively slow uniform velocity, so that the operator has enough time to present the work to the tools, by a gear train comprising a worm gear 72 fixed to the hub 60, the gear being driven by a worm 74 carried by a shaft 76 journaled in an extension of the bearing member 20 and having mounted on its end remote from the worm 74 a worm gear 78. The gear 78 is driven by another worm 80 mounted on a shaft 82 journaled in the bearing member 20 and carrying a pulley 84 at its outermost end in the plane of the pulley 24 to facilitate its being driven by the belt 22. Thus, when the motor 26 is operated, the wax-applying tool shaft 12 will be rotated and the finishing tools 48, 50, 52, and 54 will be bodily rotated with respect to the tool 10 at such a speed that each tool will remain in the vicinity of the operating point above referred to long enough to enable an operator to finish that operation for which each operating tool is intended to be used.

25 The angular spacing between the finishing tool heads 56, as illustrated herein, is irregular and is to be determined with reference to the different amounts of time required for each finishing operation, this angular adjustment of the finishing tools with respect to each other being permitted by the slots 64 and 68 which allow the heads 56 to be adjustably clamped in the turret in any desired relation to each other. It will be noted with reference to Fig. 2 that the greatest spacing between the tool heads 56 exists between that carrying the brush 54, which is the last finishing tool to be brought to the operating point during one cycle of the operation of the machine, and the padding tool 48 which is the first tool 40 to which work is presented after it has received an application of wax from the applying tool 10. This wide spacing of the padding wheel 48 and the brush 54 gives time for the operator not only to place a finished shoe aside but also to pick up one to be operated upon and to apply wax to the latter as the padding tool 48, owing to the movement of the turret, is moved to the operating point. It will be understood that the angular spacing between the finishing tools 48, 50, 52, and 54 may be adjusted at the will of the operator to suit the requirements of various types of work so that there will be substantially no loss of time between the different finishing operations. The finishing tools 48, 50, 52, and 54 are also 55 rotated about their own axes by connections comprising belts 86 which are driven by pulleys 88 which are fixed to the shaft 12 between the arm 14 and the disk 58.

Although the operation of the illustrated machine will be clearly understood from the foregoing description, it will now be summarized. The holder 30 having been adjusted to bring the wax-applying disk 28 into the desired relation to the applying tool 10 and the motor 26 having 60 been started, the operator presents the heel of a shoe to be finished to the applying tool 10 which applies and distributes the finishing medium or wax evenly over the peripheral surface of the heel. Owing to the proximity of the applying tool 10 to the operating point at which the work is presented to the finishing tools 48, 50, 52, and 54, the operator is able merely by swinging his body and without moving his feet to move the shoe from the applying tool 10 to the finishing 65 tools. After having had finishing medium or wax

applied thereto, the shoe heel will be finished by being operated upon successively by the padding wheel 48, the rand burnishing and beading tool 50 and the brushes 52 and 54. Owing to the above-described slot arrangement by which the heads 56 may be angularly adjusted relatively to each other in the turret, the spacing between the finishing tools may be readily controlled with reference to the time required for each particular finishing operation so that there will be substantially no lost time between successive finishing operations as explained above. It will thus be apparent that a minimum of effort is required of the operator in presenting the work to the applying and finishing tools and that by properly relating the speed of rotation of the turret and the spacing of the finishing tools an efficient speed in carrying out the various finishing operations is encouraged.

Having described my invention, what I claim as new and desire to secure by Letters Patent of the United States is:

1. In a shoe finishing machine, a rotating finishing medium applying tool, and a plurality of finishing tools mounted for movement bodily in a path surrounding the axis of said applying tool at a constant velocity past an operating point at which a shoe is presented to said tools in succession, said finishing tools being irregularly spaced so as to permit the operator to interchange a finished shoe for one to be operated upon and apply medium thereto during the period when the last finishing tool leaves and the first tool reaches the said operating point.

2. In a shoe finishing machine, a plurality of finishing heads each comprising a tool, a carrier for said heads, means for moving said carrier continuously whereby said tools are successively moved through an operating position at which a shoe is presented to said tools, said heads being mounted for adjustment on said carrier in the direction of its movement thereby to permit spacing said heads relatively to each other in accordance with the time required for each finishing operation.

3. In a shoe finishing machine, a plurality of finishing heads comprising tools adapted to be used in succession in finishing a shoe, a carrier on which said heads are mounted for adjustment relatively to each other, and means for moving said carrier at a uniform velocity whereby said heads are successively moved through an operating position at which a shoe is presented to said tools, the space between that head used to complete the finishing of one shoe and that used to begin the finishing of the succeeding shoe being greater than the space between successive heads used in finishing the same shoe thereby to compensate for the time required in substituting for a finished shoe one to be operated upon.

4. In a shoe-finishing machine, a tool for applying finishing medium to a shoe, a turret carrying a plurality of rotating tools to which a shoe having had medium applied thereto is presented, and means for continuously rotating said turret whereby said rotating tools are bodily rotated with respect to said applying tool, the last and first tools on said turret to which the shoe is presented being spaced from each other at a greater distance than that between other successive tools thereby to permit the interchange of a finished shoe for one to be operated upon and the application of medium to the latter by the use of said applying tool.

5. In a shoe-finishing machine, a tool for ap-

plying finishing medium to a shoe, and a plurality of finishing tools adapted for use in succession to finish a shoe to which finishing medium has been applied by said applying tool, said 5 finishing tools being mounted to have an orbital movement about said applying tool.

6. In a shoe-finishing machine, a plurality of shoe-finishing tools adapted to be used in succession, a turret on which said tools are rotatably 10 mounted, and means for rotating said turret at a constant angular velocity, the angular space between that tool used to complete the finishing of one shoe and that used to begin the finishing of the succeeding shoe being substantially greater 15 than the angular spacing between successive tools used in finishing the same shoe.

7. In a finishing machine, a plurality of finishing heads comprising tools adapted to be used in succession in finishing a shoe, a continuously 20 rotating turret on which said heads are angularly spaced at different distances in accordance with the time required for the respective finishing

operations, and a finishing-medium-applying tool mounted to rotate about the axis of said turret.

8. In a finishing machine, a rotatable shaft, a tool on said shaft for applying finishing medium 5 to a shoe, a plurality of finishing tools, a turret carrying said finishing tools and mounted to rotate about the axis of said shaft, means for rotating said turret and shaft, and connections operated by said shaft for rotating said finishing 10 tools.

9. In a finishing machine, a tool for applying finishing medium to a shoe, a shaft on which said tool is mounted, a turret comprising a sleeve in which said shaft is rotatably supported, a plurality of finishing tools mounted on said turret for angular adjustment about the axis of said turret, means for rotating said turret and shaft, and connections between said shaft and said 15 finishing tools for rotating the latter. 20
